UNITED STATES PATENT OFFICE.

JOHN WALLACE HALL, OF FELTHAM, ENGLAND.

INTERNAL-COMBUSTION ENGINE.

Application filed March 4, 1920. Serial No. 363,357.

To all whom it may concern:

Be it known that I, JOHN WALLACE HALL, a subject of the King of Great Britain, residing at Feltham, Middlesex, England, have invented certain new and useful Improvements in Internal-Combustion Engines, of which the following is a specification.

This invention relates to improvements in four-stroke cycle internal combustion engines of the type employing a reciprocating sleeve valve mechanism. It is especially applicable to a multi-cylinder engine having a plurality of cylinders around a central crank case, and to a double series of such cylinders arranged in adjacent parallel planes at right angles to the centre line of the crank shaft.

One of the objects of my invention is to facilitate the admission of the combustible mixture into the cylinders and the ejection of the exhaust gases therefrom simultaneously with an efficient scavenging operation, and a particular object is the construction of an engine with simplified valve mechanism and cylinder construction of such a nature that the engine may be built in a very light form for evolving a considerable amount of power.

My invention is especially applicable to air craft work where much power for light weight and small size is essential, and I claim to obtain this in a greater degree, by my invention, than hitherto.

To this end, the invention comprises the construction of a series of radial cylinders around a crank case, the provision of a single sleeve valve for each cylinder, the provision of exhaust ports in each cylinder at the outer end thereof opening preferably direct into the atmosphere, and the provision of inlet ports to each cylinder at the opposite end, either in communication with an outside supply of combustible mixture, or with a supply from the crank case, the feature of these inlet ports being that they do not open until just before the end of the suction stroke, while air is admitted freely during the first half of the said stroke through the exhaust ports, and then reduced in pressure during the second half of the stroke, the admission being achieved without any possibility of redrawing in the exhaust products of combustion from the previous stroke, and so that when the combustible mixture enters, there is a pressure below that of the atmosphere in the cylinder. An-

other feature of the construction with regard to the opening of the inlet ports is that the movement of the sleeve on the firing stroke is different to that on the induction stroke, whereby there is no possibility of the products of combustion passing to the induction passage and thereby diluting the incoming mixture, as is the case in some other well known engines.

The sleeve valve may be constructed of a thin cross section in order that it shall have sufficient flexibility to render it expansible at the higher pressure in the cylinder.

By this means a construction is obtained whereby one plane may have a series of cylinders, say nine, completely around a crank case; the second plane may have a similar series of cylinders, say nine, also around the crank case and staggered in relation to the first series, whereby an impulse may be given to the crank shaft substantially at nine different points of the crank circle on each revolution, and very good equalization of torque may thus be imparted to the crank shaft.

The accompanying drawings illustrate a preferred form of this invention.

Fig. 1 is a side view partly in section, developed on the line ABC of Fig. 2 through the middle of an engine having a double series of cylinders.

Fig. 2 is an end view partly in section approximately at a line such as X, Y, Fig. 1 passing between the two sets of cylinders so as to indicate the valve mechanism;

Fig. 3 is a modified view showing the valve sleeve without exhaust ports, and a single row of exhaust ports in the cylinder;

Fig. 4 is a diagrammatic view illustrating the sleeve operating discs attached to the crank shaft so that one groove can be seen in relation to the other;

Figs. 5, 6, and 7 illustrate diagrammatically particular positions of the sleeve and the piston respectively at particular points of the cycle, it being noted however that as shown in these views the induction passage is not necessarily connected with the crank case.

These Figs. 5, 6, and 7 show the arrangement of exhaust ports used where the cylinder is exposed to a natural draught of air such as caused by the passage of the engine through the atmosphere, as on an aeroplane, while Fig. 8 illustrates the arrangement of

ports when the cooling air is admitted under pressure.

Fig. 9 shows a modified construction in which the ports of the cylinder are controlled by poppet valves.

Referring to the drawings, 1, 2, 3, 4 are all particular cylinders of the engine, the odd numbers, 1, 3, etc., being in one plane, and the even numbers 2, 4, etc., being in an adjacent plane parallel with the first. Each cylinder is provided with a sleeve such as 20 working within a cylinder, which is provided preferably at its outer end with a series of exhaust ports 21, 22, and the sleeve is provided at its inner end with a series of induction ports 23, 24. The exhaust ports open into the outside atmosphere, and in the particular engine illustrated the induction ports 23 open into the induction passage 25 which is in communication with the crank chamber through the series of ports 24. The passage 25, instead of being connected with the crank chamber, may equally well be connected with some other source of fuel supply, see Figs. 5, 6, 7.

26 is the crank shaft, 27 the connecting rod, and 30, 31, 32, and 33 are plates or discs, the discs 31 and 32 being connected by a suitable jointing arrangement as shown at 29, these discs 30, 31, 32 and 33 practically forming crank webs for the shaft 26. The outer end of the crank shaft bearings will be of ordinary character, but in order to provide a satisfactory bearing for the inner plates 31, 32, which also act as cams for working the sleeve valve, roller bearings 28 are provided which support the said cam discs on bearing races 34 carried by the casting of the crank case. Valve rods, such as 35, 36 connect the sleeves 20 with cam grooves 40, 41 by means of shuttle pins such as 37, so called because they move transversely from the groove 40 into relation with the groove 41 and back again according as they are actuated by inclines in the said grooves. The purpose of this arrangement is so that the sleeve 20 may be actuated on the firing and exhaust strokes, by the groove 40, and on the induction and compression strokes by the groove 41 in order that the movement of the said sleeve shall be different, and the reason for this is that the engine working on a four-stroke cycle, the movement of the sleeve requires to be different on each alternate revolution, in that it is desirable to have a longer closing of the exhaust ports on the firing stroke than during the corresponding induction stroke during which the exhaust ports admit air.

As will be seen from the drawing, each sleeve is operated by a rod such as 35, 36, a number being disposed radially around the centre line of the crank shaft for the series of cylinders 1, 3 and the like, and a number 45 being disposed substantially in the same

plane and operated by the same grooves 40, 41 to move the sleeves in the series of cylinders 2, 4 and the like.

Referring to Figs. 5, 6, and 7, in which the cooling air enters naturally due to the position of the engine, the cycle of operations is as follows:

On the firing stroke, by means of the groove 40 the sleeve is stationary and the exhaust ports closed, except that at the end of the firing stroke the sleeve moves inward (i. e. towards the crank shaft) so that the inlet ports are not uncovered by the piston at the end of the stroke, (see Fig. 5) and at the same time exhaust ports 21, 22 are opened. Fig. 5 shows the position at the bottom dead centre, the exhaust ports being partly open with the sleeve moving inwards with maximum rapidity, and it should be noticed in connection with this exhaust stroke that the cylinder remains open to exhaust not only as shown in Fig. 6, which is the top of the exhaust stroke, but for approximately a further half stroke inwards during the following induction stroke, and during which pure air is drawn into cylinder through exhaust ports 21, 22. The exhaust ports therefore, are open continuously substantially for a stroke and a half to the atmosphere, and as shown in Fig. 6, they are fully open at the end of the exhaust stroke, and in such a way that there will be a complete scavenging of the combustion chamber from one side to the other by air passing across the said chamber, which must completely remove any spent gases which might otherwise remain, as well as cooling the interior of the combustion chamber. This is a point of considerable value as it not only prevents overheating of 100

spark plug and piston, but increases percentage of oxygen present in the cylinder, with consequent increase in power.

Fig. 7 shows the position as the crank is about to pass over the bottom dead centre on the inlet stroke; the exhaust ports having been closed for the latter half of this stroke and the sleeve in the position being stationary, whereas the piston is moving inwards. For the depth of the inlet port 23, therefore, the piston uncovers same for an appreciable time, both over the end of its inward stroke and the beginning of its outward stroke. The compression stroke now takes place, the sleeve moving inward during the first part of the said stroke, until the exhaust ports in the sleeve are midway between the ports 21 and 22 in the cylinder; the sleeve now remains stationary until the end of the compression stroke, when the cycle of operations is completed. It will be noticed that the inlet ports are open and the exhaust ports closed at the end of the inlet stroke, the sleeve being stationary while at the end of the firing stroke, the sleeve is moving inwards with maximum 120

125

130

rapidity, the inlet ports being closed and the exhaust ports being opened. This is achieved by the operation of the sleeve in the cam groove 41 instead of the groove 40 owing to the shuttle pin 37 having been transferred from one to the other by an incline in the base of the groove 40 which carries the end of the pin 37 completely clear of the groove, on to a surface indeed 10 in which there is no groove present.

In Fig. 8 is illustrated the application of artificial scavenging, that is, where the pure air is forced through the cylinder as would be necessary when the engine is not opposed 15 to a natural draught, as for instance, in most cases of airship or aeroplane design.

The piston is shown at the top of the exhaust stroke; the exhaust ports 22 are open and the stream of cooling and scavenging 20 air, supplied under pressure from such source as a pump working from the crank shaft of the engine, is entering the cylinder through the conduit 8 and scavenging ports 9, which may have any suitable means 25 for regulating such supply.

The cycle of operation is the same as has been described with reference to the drawings illustrating the method of working with a natural draught, and the means of 30 closing the inlet, scavenging, and exhaust ports, which is here shown by way of example, as a sleeve valve, may be operated in any suitable manner through a member such as 35.

35 Preferably the ends of the pin 37 will be fairly thin and flat, of hardened metal, which can be slightly springing accurately fit the varying radii of the cam grooves on either side, while the centre of the pin is of 40 a cylindrical section accurately fitting a cross-head 38 on the end of the rod 35. It will be understood that a rod similar to 36 actuates a sleeve similar to 20 in each of the cylinders surrounding the crank case. With 45 an engine, therefore, having, say, nine cylinders in each plane an impulse would be given nine times in a revolution approximately at equi-distant points of the said revolution, and thereby a very regular impulse may be transmitted to the crank shaft 50 by a large number of cylinders with so simple a valve mechanism as to have but little more weight than valve mechanism often proposed for two or three cylinders only.

55 It will be noticed that there are no springs, gears, or extra shafts in the valve mechanism, and in the construction shewn, no exposed working parts. It will be also noticed, if the timing of the engine is followed, that the expansion of the sleeve takes 60 place only when gas pressures in the cylinder are high, and the sleeve is stationary, or practically so, i. e., on the latter part of the compression stroke and the majority of 65 the power stroke. By this means I am able

to do away, not only with all packing rings, but also with the detachable cylinder head.

Referring to Fig. 4, which shows the faces of the discs 31, 32 opened outwards from each other, the inclines referred to hereinbefore are shown as between the points 42, 43 and 40, 47 for the disc 31 and between the points 44, 45 and 48 and 49 for the disc 32.

70 It will be noticed that my invention is not 75 restricted to the use of a sleeve valve, or to the fuel inlet ports being at the inner end of the cylinder. For instance, an ordinary poppet valve at one side of the combustion chamber may be used for exhaust, a similar 80 valve at the opposite side may be used for the admission of air to the cylinder, and a third such valve, placed conveniently in the combustion chamber, may be used for fuel inlet. Such a construction is diagrammatically illustrated in Fig. 9, in which A 85 indicates the poppet valve controlling the air inlet D; B indicates the valve controlling the exhaust port E and C indicates a valve controlling the gas inlet F. The piston, 90 is shown at the top of the compression stroke.

I claim:—

1. In a four stroke cycle internal combustion engine, a series of exhaust and scavenging ports arranged around the high pressure end of the combustion space of each cylinder, a reciprocable sleeve valve taking bearing on each respective cylinder wall, and means for reciprocating said sleeve valve, so that the exhaust and scavenging ports are maintained open during the whole of each exhaust stroke, and for approximately the first half of each following induction stroke, comprising: juxtaposed discs coaxially mounted, and provided on their opposed faces with complementary groove paths, a rod connected to said sleeve valve and a shuttle member carried by said rod and adapted to be actuated alternately by each 100 groove path, and means for simultaneously rotating said discs.

2. In a four stroke cycle internal combustion engine, a series of exhaust and scavenging ports arranged around the high pressure end of the combustion space of each cylinder, a fuel inlet opening to said cylinder, a reciprocable sleeve valve taking bearing on each respective cylinder wall and controlling said exhaust and scavenging ports and fuel inlet as set forth, and means for actuating said sleeve valve, comprising juxtaposed discs coaxially mounted, and provided on their opposed faces with complementary groove paths, a rod connected to 115 said sleeve valve and a shuttle member carried by said rod and adapted to be actuated alternately by each groove path, and means for simultaneously rotating said discs.

3. In a four stroke cycle internal combus- 120

tion engine, a series of exhaust and scavenging ports arranged around the high pressure end of the combustion space of each cylinder, a fuel inlet opening at the opposite end of each said cylinder, a reciprocable sleeve valve taking bearing on each respective cylinder wall, and controlling said exhaust and scavenging ports and fuel inlet as set forth, and means for actuating said sleeve valve comprising juxtaposed discs coaxially mounted, and provided on their opposed faces with complementary groove paths, a rod connected to said sleeve valve and a shuttle member carried by said rod and adapted to be actuated alternately by each groove path, and means for simultaneously rotating said discs.

5. A four stroke cycle internal combustion engine including, in combination, a plurality of cylinders arranged in parallel planes, a piston for each cylinder, a ported sleeve valve between each said cylinder and piston, exhaust and scavenging ports at the explosion end of each said cylinder, inlet ports at the inner end of said cylinder disposed to be uncovered by the said sleeve valve and piston, and means for reciprocating said sleeve valve so that the exhaust and scavenging ports are opened to allow scavenging by a transverse draught and a fresh air admission, and the inlet ports are only opened towards the end of the induction stroke as set forth, said means for reciprocating each said sleeve valve comprising juxtaposed discs mounted on the engine crank shaft between each plane of cylinders and provided on their opposed faces with complementary groove paths, a rod connected to said sleeve valve and a shuttle member carried by said rod, and adapted to be actuated alternately by each groove path, all said rods lying in the same plane, disposed midway between said rows of cylinders.

6. A four stroke internal combustion engine, including in combination a crank case, a plurality of radial cylinders, arranged in two parallel rows, and in staggered relation, a piston for each cylinder, a ported sleeve valve between each said cylinder and piston, exhaust and scavenging ports at the explosion end of each said cylinder, inlet ports at the inner end of said cylinder disposed to be uncovered by the said sleeve valve and piston when at the inner end of said cylinder, and means for reciprocating said sleeve valve so that the exhaust and scavenging ports are opened to allow exhaust, scavenging by a transverse draught, and a fresh air admission, and the inlet ports are only open towards the end of the induction stroke, as set forth, said means for reciprocating said sleeve valves comprising a crank shaft, a pair of discs fixed on said engine crank shaft, and disposed equi-distant of the middle plane between the two rows of cylinders, complementary groove paths being formed on the opposed faces of said discs, a rod connected to each sleeve valve and lying partly between said discs and a shuttle member carried by each rod and adapted to be actuated alternately by each groove path.

5. A four stroke internal combustion engine, including, in combination, a crank case, a plurality of radial cylinders, arranged in two parallel rows and in staggered relation, a piston for each cylinder, a ported sleeve valve between each said cylinder and piston, exhaust and scavenging ports at the explosion end of each said cylinder, inlet ports at the inner end of said cylinder disposed to be uncovered by the said sleeve valve and piston, and means for reciprocating said

sleeve valve so that the exhaust and scavenging ports are opened to allow scavenging by a transverse draught and a fresh air admission, and the inlet ports are only opened towards the end of the induction stroke as set forth, said means for reciprocating each said sleeve valve comprising juxtaposed discs mounted on the engine crank shaft between each plane of cylinders and provided on their opposed faces with complementary groove paths, a rod connected to said sleeve valve and a shuttle member carried by said rod, and adapted to be actuated alternately by each groove path, all said rods lying in the same plane, disposed midway between said rows of cylinders.

6. A four stroke internal combustion engine, including in combination a crank case, a plurality of radial cylinders, arranged in two parallel rows, and in staggered relation, a piston for each cylinder, a ported sleeve valve between each said cylinder and piston, exhaust and scavenging ports at the explosion end of each said cylinder, inlet ports at the inner end of said cylinder disposed to be uncovered by the said sleeve valve and piston when at the inner end of said cylinder, and means for reciprocating said sleeve valve so that the exhaust and scavenging ports are opened to allow exhaust, scavenging by a transverse draught, and a fresh air admission, and the inlet ports are only open towards the end of the induction stroke, as set forth, said means for reciprocating said sleeve valves comprising a crank shaft, a pair of discs fixed on said engine crank shaft, and disposed equi-distant of the middle plane between the two rows of cylinders, complementary groove paths being formed on the opposed faces of said discs, a rod connected to each sleeve valve and lying partly between said discs and a shuttle member carried by each rod and adapted to be actuated alternately by each groove path.

In testimony whereof I affix my signature.
